UNITED STATES PATENT OFFICE.

WILLIAM F. KIESEL, JR., OF ALTOONA, PENNSYLVANIA.

ECONOMIZER FOR LOCOMOTIVES.

1,343,144.

Specification of Letters Patent.

Patented June 8, 1920.

Application filed November 11, 1916. Serial No. 130,878.

To all whom it may concern:

Be it known that I, WILLIAM F. KIESEL, Jr., a citizen of the United States, and resident of Altoona, Blair county, State of Pennsylvania, have invented certain new and useful Improvements in Economizers for Locomotives, of which the following is a specification.

This invention relates to economizers or feed water heaters adapted to be located in the stack of a locomotive.

The objects of the invention are to provide an efficient economizer or feed water heater located in the stack of a locomotive boiler; to utilize the entire space now allotted to the stack; to make such a heater from tubes; to provide a special form of nozzle to deliver steam to the heater to produce a draft for the gases; to provide a nozzle having means to distribute the steam uniformly to each tube and to provide a blower device for the tubes to create a draft when the engine is idle. Other objects will be apparent from the description taken in connection with the drawings.

In the drawings,

Figure 1 is a longitudinal sectional view through the front end of a locomotive boiler showing the general arrangement of the heater and the nozzle therefor;

Fig. 2 is a transverse sectional view showing the stack, heater and nozzle in half elevation and half section;

Fig. 3 is a sectional view taken substantially on the line 3—3 of Fig. 2;

Fig. 4 is a bottom plan view of the steam inlet for the nozzle;

Fig. 5 is a partial sectional view taken through the upper end of the stack and showing the water inlet and a pair of tubes in section;

Fig. 6 is a half plan view of the nozzle;

Fig. 7 is a plan view showing the arrangement of the blower piping.

As is clearly shown by inspection of the drawings, the structure consists of a tubular feed water heater or economizer located in the space usually allotted to the stack and extending into the smoke box of the boiler. A nozzle is arranged below the bottom of the heater and designed to receive steam and deliver it through a plurality of discharge openings to the bottom ends of the tubes of the heater. A partition is provided so that the gases must pass to the front of the smoke

box and thence through the usual netting to circulate around the tubes of the heater and be blown upward through the tubes by the steam discharged from the nozzle.

The stack shell 10 is flanged at the upper end thereof and has riveted thereto a tube sheet 11, a spacing ring 12 and another tube sheet 13 thus forming a space between the two tube sheets. In the smoke box two similar tube sheets 14 and 15 separated by a spacing ring 16 are located. Tubes 17 are expanded at their ends into the two outer tube sheets 13 and 14 and surrounding these tubes are tubes 18 of larger diameter which are expanded into the inner heads 11 and 15. Thus annular spaces are formed around each of the tubes 17 and these spaces are connected to the top and bottom spaces formed between the tube sheets. The space between the upper tube sheets is provided with an inlet 19 and the space between the lower tube sheets is furnished with an outlet 20 oppositely located with respect to the said inlet. The said upper space is divided by a partition 21 so that the water entering through the inlet 19 is obliged to pass downward through the two left-hand rows of tubes as viewed in Fig. 5. The space between the lower tube sheets is divided by a partition 22 located so that the water cannot pass upward through the two right-hand rows of tubes as viewed in Fig. 2. It will thus be apparent that circulation of water fed to the inlet by the pump injector or any other means is downward through the two left-hand rows of tubes, upward through the two central rows of tubes and downward to the outlet through the two right-hand rows of tubes. Of course these partitions and the circulation of water may be varied to suit the number of tubes and the arrangement thereof.

A nozzle A for delivering steam to the lower ends of the tubes is located just below the lower tube sheets. As will be apparent from the drawings this nozzle is substantially cone shaped and is hollow. The part corresponding to the apex is formed with a steam inlet opening 23 and the base thereof is formed with a plurality of discharge openings 24. These openings extend upward through projecting smaller nozzles 25, and one of these smaller nozzles is furnished for each of the tubes and is located substantially centrally with respect to the same.

The nozzle is provided with one or more conical walls 26, 27 which form passages leading from the inlet to the discharge openings. The wall 26 is formed with an inlet 28 and the wall 27 with an inlet 29. From Fig. 4 which is a bottom plan view of the inlet to the nozzle it will be observed that the inlets 28 and 29 are so positioned that each will receive some of the entering steam. Furthermore the areas of these inlets is such that each one will take the proper amount of steam to furnish equal quantities thereof to each of the discharge openings. Thus some of the steam entering through inlet 23 passes through the opening 28, the remainder being deflected by the edges of the opening and passing into the conical space between the wall 26 and the outer wall of the nozzle. The steam which is caught in this outer space is just sufficient to supply the discharge openings 24 which are connected with the said space. Of the steam which enters through the opening 28 some passes through the opening 29 and the remainder is caught by the edges of the opening and delivered into the passage between the conical walls 26 and 27. It will be obvious that it is merely a question of design to so proportion these openings that each one will take steam in ratio to the number of discharge openings that it supplies. Consequently the nozzle is furnished with means for delivering equal quantities of steam to each of the discharge openings. This results in creating a uniform draft through all of the tubes of the heater and consequently in obtaining a uniform heating from each of the tubes.

Just below the lower tube sheet a header 30 is supported and is provided with a plurality of branches 31 each having a plurality of upwardly extending discharge tubes 32, each of the latter being located adjacent the edge of a tube 17. This arrangement constitutes a blower, which is used to create a draft when the locomotive is not running, at which time the blower is made to take live steam direct from the boiler.

It will be noted that the space in the smoke box is divided into two compartments by plates 33, 34 and 35, the latter being attached to the bottom of the spark arrester netting 36. Thus it will be apparent that the gases will pass around the nozzle through the netting and will circulate around the tubes of the heater and finally be blown up through the tubes of the same by the steam blast. As these gases are at a high temperature they will in their circulation around the tubes of the heater and through the same give up considerable heat which will be absorbed by the water in the heater. Furthermore the heater will abstract some of the heat from the steam used to create the draft.

It will be obvious that this heater is

adapted for use in locomotive boilers of different types, that is, it can be used in boilers with or without superheaters and in stationary locomotive boilers or locomotive engine boilers. Although a specific embodiment of the invention has been described it is apparent that many of the details may be varied without departing from the spirit of the invention. 70

Having thus described the invention what is claimed and desired to be secured by Letters Patent is:

1. In combination with a feed water heater for locomotive boilers, a steam nozzle having a plurality of discharge openings 80 and formed with internal passages, the cross sectional area of the passages being proportional to the area of the openings leading from each passage.

2. In combination with a locomotive boiler 85 having the usual smoke box and stack shell, spaced apart tube sheets arranged at the top of said shell, similar spaced apart tube sheets arranged below said shell and in the smoke box, a series of inner tubes carried 90 by the end tube sheets, a series of outer tubes surrounding the first series and carried by the inner tube sheets whereby water spaces are formed between the tubes and the tube sheets and the products of combustion 95 are circulated around the outer tubes and up through the inner tubes, an inlet for the space between said upper sheets and outlet for the space between said lower sheets, and means for discharging equal quantities of 100 steam into the lower end of each of the inner tubes.

3. In combination with a locomotive boiler having the usual smoke box and stack shell, spaced apart tube sheets arranged at the 105 top of said shell, similar spaced apart tube sheets arranged below said shell and in the smoke box, a series of tubes carried by the end tube sheets, a series of tubes surrounding the first series and carried by the inner 110 tube sheets whereby water spaces are formed between the tubes and tube sheets, an inlet for the space between said upper sheets and outlet for the space between the lower sheets, and means for discharging exhaust steam 115 into the lower ends of the inner tubes and a pipe at the lower end of each inner tube for delivering live steam.

4. In a locomotive boiler having a tubular feed water heater in the stack, a nozzle for 120 delivering steam to the heater comprising a substantially hollow cone having a plurality of discharge openings in its base and an inlet at the apex and one or more spaced conical walls arranged in the cone and having 125 inlets at their apices.

5. In a locomotive boiler having a tubular feed water heater in the stack, a nozzle for 130 delivering steam to the heater comprising a substantially hollow cone having a plurality

of discharge openings in its base and an inlet at the apex and means for carrying equal quantities of steam to the openings.

6. In combination with a locomotive boiler having a smoke box and stack shell, a feed water heater in said shell and extending into the smoke box, said heater including a series of inner tubes, a series of outer tubes surrounding the inner tubes, walls around 10 the portion of the heater in the smoke box, one wall being formed to admit the products of combustion for circulation around the outer tubes and up through the inner tubes, and means for delivering substantially equal quantities of steam at the bottom of each inner tube.
7. In combination with a locomotive boiler having a smoke box and stack shell, walls within the smoke box inclosing a space at 20 the bottom of the stack, the stack and said walls thus forming a chamber, a tubular feed water heater arranged in said chamber, one of the walls being formed to admit the products of combustion for circulation around the heater and up through the tubes and means for delivering equal quantities of 25 steam to the lower end of each of the tubes of the heater.

steam to the lower end of each of the tubes of the heater.

8. In combination with a locomotive boiler having a smoke box and stack shell, walls 30 within the smoke box inclosing a space at the bottom of the stack, the stack and said walls thus forming a chamber, a tubular feed water heater arranged in said chamber, one of the walls being formed to admit 35 the products of combustion for circulation around the heater and up through the tubes and another wall having means for delivering equal quantities of steam to the lower end of each of the tubes of the heater. 40

9. In combination with a locomotive boiler having a smoke box and stack shell, a tubular feed water heater in said stack shell projecting into the smoke box and means for effecting a circulation of the products of 45 combustion around the heater tubes and thence up through the heater including a device having a steam outlet at the lower end of each of the tubes of the heater.

In testimony whereof I affix my signature. 50

WILLIAM F. KIESEL, JR.
